UNITED STATES PATENT OFFICE.

LASSAR J. GRINBERG, OF NEW YORK, N. Y.

DESIGN FOR A GAS-STOVE.

SPECIFICATION forming part of Design No. 27,612, dated August 31, 1897.

Application filed July 14, 1897. Serial No. 644,576. Term of patent 31 years.

To all whom it may concern:

Be it known that I, LASSAR J. GRINBERG, of New York city, county and State of New York, have invented and produced a new and 5 original Design for Gas-Stoves, of which the following is a specification, reference being had to the accompanying drawings, forming part thereof.

Figure 1 is a perspective view of a gas-stove, 10 showing my new design. Fig. 2 is a cross-section on line 2 2, Fig. 1.

The leading feature of my design consists of a gas-stove having a frame, a central perforated plate, and front and rear ribs that extend across such plate and also across the open 15 spaces to the sides thereof.

a a represent a rectangular frame supported upon legs *b*. At the center the longi-

tudinal rails of frame *a* merge into a stove-plate *c*, having a central perforation *c'*. Across 20 the plate *c* and partly across the perforation *c'* extend parallel front and rear transverse ribs *d d'*. To the right and left of plate *c* the frame *a* is open, each open space being also spanned by front and rear transverse ribs *e e'*, 25 placed above the burners *f*. Beneath the plate *c* there is arranged an oven *g*, having flanges *g'*.

What I claim is—

The design for a gas-stove, substantially as 30 herein shown and described.

LASSAR J. GRINBERG.
